a corporation of New York

Application March 14, 1951, Serial No. 14,491

Term of patent 14 years

(Cl. D36—2)

To all whom it may concern:

Be it known that I, Albert J. Dreitzer, a citizen of the United States of America and a resident of New York, in the county of New York and State of New York, have invented a new, original, and ornamental Design for a Glass Plate or Similar Article, of which the following is the specification, reference being had to the accompanying drawing, forming a part hereof.

Figure 1 is a top plan view of a glass plate or similar article showing my new design.

Figure 2 is a vertical cross-sectional view taken along line 2—2 of Figure 1.

Figure 3 is a partial vertical sectional view taken along line 3—3 of Figure 1.

Figure 4 is a partial vertical sectional view taken along line 4—4 of Figure 1.

Figure 5 is a partial vertical sectional view taken along line 5—5 of Figure 1.

I claim:

The ornamental design for a glass plate or similar article, substantially as shown.

ALBERT J. DREITZER.
